CARBURETOR

Filed April 27, 1927

INVENTOR

John J. Langdon.

BY

Arnold E. Putrich

ATTORNEY

UNITED STATES PATENT OFFICE.

JOHN J. LANGDON, OF HARTFORD, CONNECTICUT.

CARBURETOR.

Application filed April 27, 1927. Serial No. 186,986.

My invention has for its object to provide a carburetor having provision for forcing a supply of gaseous mixture to the engine's cylinders instead of depending upon the suction created during the suction stroke of the engine's piston. In carburetors such as heretofore used, which depend upon the suction of the engine to charge the cylinders, when a car is climbing a hill and the pistons move up and down at a slow speed the suction of the gasoline is proportionally slower, at the very time the cylinders need the most gasoline and thus they receive a leaner mixture than should be supplied to the cylinders in order to maintain the most effective operation; my invention therefore has for an object to provide means for charging the cylinders independent of the suction stroke of the piston.

20 The invention also has for its object to provide means by which the usual vacuum tank may be dispensed with and the carburetor itself function to maintain a supply of gasoline in the float chamber at all times.

25 With other objects in view the invention consists in providing a carburetor with a fan or blower for forcing air past a Venturi tube through the neck of the carburetor into the engine's cylinders, thereby atomizing the gasoline drawn from a reservoir through the Venturi tube; means are provided for regulating the feed of air in conjunction with the throttle action, and the usual float and needle valve is provided for 30 maintaining a constant level of gasoline in the outlet reservoir; invention also resides in the provision of a vacuum device for drawing the gasoline from the storage tank (located at a lower level) and feeding it 35 into the float chamber of the carburetor when the needle valve is open, thus maintaining a constant supply of atomizable fluid in the carburetor.

40 The invention furthermore resides in those novel details of construction, combination and arrangement of parts, all of which will be first fully described, then be particularly pointed out in the accompanying drawing, in which:—

45 Figure 1 is a perspective view of a carburetor employing my invention and showing the connection between the throttle valve and the air inlet shutter or valve.

Figure 2 is a vertical longitudinal section of the same.

55 Figure 3 is a diagrammatic side elevation showing the use of an electric motor for driving the fan, this being an arrangement especially adapted when the carburetor is to be used in connection with fuel burners.

60 In the drawing in which like numerals of reference indicate like parts in all the figures, 1 represents the float chamber, 2 the outlet reservoir, 3 the Venturi tube through which the gasoline is drawn from the outlet 65 reservoir 2 into the neck 4 of the carburetor.

70 The neck 4 is flanged at 5 so as to be coupled with the intake manifold (not shown), and the neck 4 is provided with the usual butterfly throttle valve 6 that is operated by a suitable operating rod 25 in the ordinary manner.

75 A sediment cup 7 is provided beneath the float chamber 1 and communicates with that chamber through a duct having a needle valve seat 9 with which the needle valve 10 that is controlled by the float 11 cooperates. The construction of the needle valve and the float may be of any of the usual types and per se constitutes no part 80 of the present invention.

85 A port 12 is provided between the float chamber 1 and outlet reservoir 2 so that the level of gasoline in the reservoir 2 may be maintained constant by re-supply from the float chamber.

90 13 designates the fan or blower chamber having an outlet throat 14 connecting with the neck 4 and the chamber 13 is provided with a cap 15 having ports 16 as shown. 17 is the shaft outer bearing on the cap 15 in which the blower or fan shaft 18 is journaled, the shaft 18 carrying the fan or blower 19 and projecting into a bearing 20 at the inner end as shown best in Figure 2 95 of the drawing.

99 21 is the shutter-valve which is ported to register with the ports 16 when in one position and to close those ports when in another position, the shutter 21 having a handle 22 connected by a bell crank 23 with the throttle valve lever 24 so that movement of the throttle valve to open and close the neck passage will correspondingly open and close the air ports 16.

105 26 is a suction tube which is connected at

one end with the throat 4 and at its other end is connected with the vacuum chamber 27, the latter having a valve seat 28 to cooperate with the check valve 29. The check valve is 5 operated by a float 30 in the chamber 27. Spacing lugs 31 are provided within that chamber so that the float 30 may not close the entrance to the chamber through which 10 the stand pipe 32 effects communication with the interior of the chamber. The stand pipe 32 is coupled at 33 and 34 with the sediment chamber 7 and supply line 35 respectively, back check valves being provided at the 15 couplings 33 and 34 (or at any other suitable point in the connection between the stand pipe 32 and the supply or storage tank).

The check valve 29 is preferably provided with a duct 36 having two ports 37 and 38, the port 38 always communicating with the 20 interior of the chamber 27 and the port 37 communicating alternately with the port 39 that delivers into the vacuum or suction pipe 26 and the port 40 which communicates with atmosphere, the communication between 25 37 and 40 occurring via the recess 41.

In operation, power is applied to the shaft 18 by means of a pulley 42, see Figures 1 and 2, or an electric or other suitable motor 43, see Figure 3, so as to force air through 30 the throat 14 and neck 4 to the engine's cylinders. The action of this air causes a partial vacuum in the outlet end of the Venturi tube 3 and also at the end of the pipe 26 that communicates with the throat 4. 35 This partial vacuum causes gasoline to be drawn through the Venturi tube and vaporized and mixed with the air that is being forced to the engine's cylinders to produce the required charge. The partial vacuum produced also causes suction in the pipe 26 which, when the float 30 is down and the 40 valve is set to effect communication between ports 39 and 37, will draw gasoline from the storage tank into the stand pipe 32. As 45 the float 30 rises the communication between ports 37 and 39 will be terminated and the interior of the reservoir 27 will be connected with the atmosphere through port 40, thereby permitting the gasoline in the stand 50 pipe 32 to flow by gravity into the float chamber 1 in the event that the needle valve is off its seat. As soon as the float has again closed the port and the level of gasoline in the stand pipe has lowered sufficiently to 55 bring the ports 37 and 39 into communication again the operation of drawing a supply of gasoline from the storage tank in the stand pipe will be repeated.

Not only may this invention be used in 60 connection with carburetors in internal combustion engines, but it can be used to produce a burning mixture for oil fuel burners and the like as diagrammatically indicated in Figure 3 of the drawing.

65 From the foregoing description, taken in

connection with the accompanying drawing, it is thought the complete construction, operation and advantages of my invention will be clear to those skilled in the art to which it relates.

What I claim is:

1. A carburetor comprising a float chamber having an inlet and a float controlled needle valve associated with the inlet, a neck constituting a mixing chamber, an outlet reservoir in communication with the float chamber and including a delivery tube communicating with said neck, said carburetor also including a blower chamber and a blower for forcing air into said neck adjacent the tube, a shutter valve controlling the air admission to the blower, a throttle valve in the neck, a connection between said throttle valve and said shutter valve whereby manipulation of the throttle valve will cause corresponding manipulation of the shutter valve, said carburetor including a vacuum chamber, a suction pipe connecting the vacuum chamber with said neck, a stand pipe communicating with the vacuum chamber and with said float chamber through the needle valve opening, a connection between said stand pipe and the source of liquid fuel supply, and a float controlled valve in said vacuum chamber for the purposes described. 90

2. In a carburetor, the combination with the float chamber having an inlet controlled by a needle valve and float, a neck constituting a mixing chamber, an outlet reservoir in communication with the float chamber, a tube effecting communication between the outlet reservoir and the neck, a blower chamber, a blower mounted in said blower chamber, means for driving said blower, controlled means for admitting air into said blower chamber, said carburetor including a throat between said blower chamber and said neck through which the air is forced by said blower, a throttle valve in said neck, means for controlling the admission of air into said blower chamber, means connecting said air admission controlling means and said throttle valve for simultaneous operation, a vacuum chamber, a stand pipe connecting said vacuum chamber with the inlet port of said float chamber, a back check valve in said connection, means connecting said stand pipe with the source of fluid supply, means connecting said vacuum chamber with said neck, said last named means including a vacuum-float check valve. 115

3. In a carburetor, the combination with the float chamber having an inlet controlled by a needle valve and float, a neck constituting a mixing chamber, an outlet reservoir in communication with the float chamber, a tube effecting communication between the outlet reservoir and the neck, a blower chamber, a blower mounted in said blower chamber, means for driving said blower, con- 125

trolled means for admitting air into said blower chamber, said carburetor including a throat between said blower chamber and said neck through which the air is forced by said blower, a throttle valve in said neck, means 5 for controlling the admission of air into said blower chamber, means connecting said air admission controlling means and said throttle valve for simultaneous operation, a 10 vacuum chamber, a stand pipe connecting said vacuum chamber with the inlet port of said float chamber, a back check valve in said connection, means connecting said stand pipe with the source of fluid supply, a suction

duct connecting said vacuum chamber with 15 said neck, said last named means including a vacuum-float check valve, said check valve comprising a float member, a valve stem having a passage with a port adapted when said valve stem is in one position to effect communication between said vacuum chamber and the suction duct connecting the vacuum chamber with the neck and when in another position to close off such communication and effect communication between the interior of 20 said vacuum chamber and the atmosphere for the purposes described.

JOHN J. LANGDON.
